[57] **CLAIM**

The ornamental design for a utility tray, as shown and described.

DESCRIPTION

FIG. 1 is a top plan view of a utility tray showing my new design;

FIG. 2 is a side elevational view thereof, the side opposite being a mirror image;

FIG. 3 is a cross-sectional view thereof taken along line 3—3 in FIG. 1, shown on an enlarged scale;

FIG. 4 is another cross-sectional view thereof taken along line 4—4 in FIG. 1; and,

FIG. 5 is another cross-sectional view thereof taken along line 5—5 in FIG. 1.
